NATHAN H. SPAFFORD, OF BALTIMORE, MARYLAND.

Letters Patent No. 61,480, dated January 22, 1867.

IMPROVED MACHINE FOR COMBING AND ASSORTING BRISTLES.

The Schedule referred to in these Letters Patent and making part of the same.

TO ALL WHOM IT MAY CONCERN:

Be it known that I, NATHAN H. SPAFFORD, of Baltimore, in the county of Baltimore, and State of Maryland, have invented a new and useful Machine for Combing and Assorting Bristles; and I do hereby declare the following to be a full and exact description thereof, reference being had to the annexed drawings, making part of this specification.

Figure 1 is a plan or top view of my invention.

Figures 2 and 3 are elevations of opposite sides of the machine.

Figure 4 is a vertical section on the line X X of fig. 1.

Figure 5 is a vertical section and elevation on the line XI XI of fig. 1.

Figures 6, 7, and 8 show parts in detail, to be more particularly referred to hereafter.

In all the figures, like parts are indicated by the same letters of reference.

The nature of my invention consists in so constructing and combining together the parts of my machine, that any fibrous matter subjected to its operation, as straw, grass, hair, wool, bristles, &c., that may be in a tangled, matted, or confused mass, can be quickly and easily brought to a condition of regularity and uniformity, insuring parallelism of all the fibres, without risk of injury, while all foreign matter, or offal, from the material itself will be excluded, and nothing will remain but that which is desired. It is not contemplated that necessity will very soon exist for the use of the machine in treating any other material than bristles, and accordingly that article will be referred to in this specification as the object-matter of the invention.

A A A A is the framework of my machine; B is a shaft supported in bearings on the frame A, and receives motion from any source deemed most expedient, being made to revolve in the direction indicated by the arrow. Other arrows indicate the direction of motion in other parts of the machine. On the shaft B is set a spur-gear, C, by which, through the spur-gears C', C'', and D, the other parts of the machine are operated. Two endless aprons E and E', seen in section, fig. 4, travel upon rollers having their bearings in the standards a a. The upper apron E, which is the one upon which the irregular and tangled mass of bristles is fed to the machine, has a continuous motion which is derived indirectly from the spur-gear D, through the pinions b b', shaft F, and pinion b'', which last drives the spur-gear G on the shaft c; a band or cord from the shaft c to a pulley, d, on one of the apron-rollers, causes it to revolve. The shaft F revolves much more rapidly than the rollers carrying the apron E, and carries a cylinder, equal in length to the width of the apron, which cylinder is furnished with teeth or pins, so as to form a picker or hatchet F', and act as such upon the tangled mass of bristles which has been fed upon the apron E. A roller, e, of gum or other suitable material, rests on the apron E, over its driving-roller, and serves to keep the bristles from being swept down before they have been properly acted on by the picker. The endless apron E', which is under the apron E, has an intermittent movement, which lasts, say, during one-eighth of a revolution of the main driving-shaft B, and which is derived from an arm, f, seen dotted in figs. 1 and 2, which projects from the face of the spur-gear D, and comes in contact once, in every revolution of the gear, with teeth or pins, f', projecting radially from the end of the axle of a roller of the apron E. A gum-roller, e', rests over the apron E', for the same purpose as the roller e over the apron E; and these two rollers, e' and e, have a slight vertical play in their bearings, so that they may accommodate themselves to inequalities in the materials which may pass under them, and are kept down to a proper degree of pressure upon the bristles by means of weights or an equivalent device. The gum-roller e' is geared at one end with the driving-roller of the apron E', so that the two shall revolve together in the same time and at the same rate. On the same shaft with the spur-gear C'', and revolving with it, is a segment-toothed wheel, H, having teeth for only two-thirds of its periphery. The wheel H drives the shaft g by means of the pinion h, and causes the shaft to make two revolutions while the main driving-shaft B makes two-thirds of a revolution; during the other third of the rotating of the shaft B, the shaft g is at rest, being kept from turning by the dog i, which catches in a notched tumbler i', on the shaft g, and is kept in the notch by a spring or equivalent until just before the teeth of the segment H have again engaged with those of the pinion h, when a cam, H', (see in dotted lines, fig. 2,) operates on the trigger of the dog i so as to leave the shaft g free to turn at the proper time. The shaft g has a crank at that end which is opposite to the pinion h; the crank-arm or wrist I of the crank passing through and turning in the arm of the comb J. From the arm of the comb projects a stem, J', which passes through and traverses in a slide free to vibrate upon a joint at K, the joint being rendered adjustable by means of a slot and set-screw,

as seen in fig. 1. The comb J, seen in figs. 3, 4, and 5, has a gauge, k, attached to it in such a manner that the teeth of the comb may be cleared of anything that may adhere to or between them or tend to clog or choke them. Through the ends of the comb-plate or stock in which the teeth are secured, pass the arms k' of the gauge k, which is attached to the arms and rests close upon the teeth of the comb. The lower edge of the gauge k has notches cut in it corresponding in number and size with the teeth of the comb; the edge is then turned in so that the teeth will pass through the notches in the gauge. A spring, l, secured to the centre of the comb-stock, and pressing against studs at the ends of the gauge k, keeps the gauge k always up towards the stock of the comb; until the arms k' are forced down through the ends of the stock, by coming in contact with the cams m m on the shaft g, and crank-wrist I, as these revolve, when the gauge k is forced towards the ends of the comb-teeth, and clears them of whatever may have been between them. Projecting from the inner face of the spur-gear D is a stud, n, (seen in dotted lines in fig. 2,) which, as the gear revolves, comes in contact with and moves the toe n' on the rock-shaft L, which has its bearings in the standards a a, and gives vibration vertically to the lower gauge-plate M, with which it is connected by arms, (see fig. 4.) The crank-wrist I and the stud n are so related to each other and to the segment-gear H, that when the comb-teeth are brought down immediately in front of the endless apron E', after making the movement twice without stopping, the lower gauge-plate M is brought up by the vibration of the rock-shaft L, so that its upper edge shall be against the under side of the bristles just combed out straight, and the gauge k is on the top of the bristles, which are thus projecting between the two gauges, and are divided in small quantities by the teeth of the comb, which pass down through them. This position of the comb J and gauges M k is maintained while the toothless part of the segment H is passing without driving the pinion h. Supported on a portion of the framework are the slides N N, along which traverses the bed-plate N' of the nipper-jaws O. This sliding movement is effected by means of a crank-pin on the end of the main driving-shaft B, which plays in a curved slot in the lever O', having its fulcrum at p, and passing up into and through the bed-plate N'. The nipper-jaws O are as wide at the mouth as the endless aprons, and are intended to embrace the whole of the bristles which may be presented to them by the action of the comb J and gauge-plate M. They are hinged together at o, and are prolonged in the opposite direction from their lips into levers O'' O'', connected at their extremities by links, q q, that form a toggle-joint, the pin q' of which projects on each side so as to rest in slots through the standards r r, which support the direct moving devices of the jaws. The office of the toggle-joint q is to insure uniformity in the movements of both jaws O. The lip of the upper jaw is provided with an elastic yielding material forming a cushion against which the bristles may not be broken or even bruised when seized with force enough to drag them from between the apron E' and the roller e'. A portion of each end of each jaw is extended beyond the axis o on which they move, so as to form levers, which are kept apart by loop-shaped springs s s, (figs. 1 and 3,) thus forcing the lips of the jaws together, when they are not overcome by the devices for opening them. Supported on standards rising from the bed-plate N' is a shaft, P, carrying at one end a windlass, P', and at the other end a tumbler, t, while on that portion which is between the levers O'' O'' is a cam, R, so constructed as to cause the jaws to open when turned between their levers O'' O''. On the shaft B is a toe-cam, Q, by which vibration is given to the lever Q'. To the end of this lever is attached one end of a chain, which is secured by its other end to the windlass P'. From the windlass another chain extends in an opposite direction to a standard rising from one of the slides N, to which it is firmly secured. As the crank-pin on the shaft B (see fig. 4) turns in the slot in the lever O', the head of the lever moves the bed-plate N' and the jaws O back from the comb J. Tension is produced in the chain from the lever Q' to the windlass P', causing this last to turn, and with it the cam R, so that its pressure against the inner surfaces of the two levers O'' O'', causes them to open, as seen in section, fig. 4. As the shaft P, by the action of the chain on the windlass P', continues to revolve, the tumbler t, engaging with the slotted connecting-bar t', causes, by its action on the shaft t'', the double-dog u u to engage in such a manner with the two levers O'' O'' as to keep them open after they have been relieved from the action of the cam R, until it shall have become necessary to close the jaws again. As the rotation of the shaft B continues, the bed-plate N' is brought forward towards the comb again, and the chain from the lever Q' to the windlass is loosened, and motion is given in a contrary direction to the windlass and its shaft, by a strain on the chain attached to the slide N, whereby the cam R is turned so as to be out of contact with the levers O'' O'', leaving them propped apart by the dog u u until the lips of the jaws have nearly reached the comb and have received between them the bristles presented by the action of the comb and gauge-plates. At this point in the movement of the machine, a lever, v, on the shaft t'', comes in contact with a stud or post, S, causing the dog u u to be turned so that it is disengaged from the levers O'' O'', and the jaws are closed with a snap upon the bristles between them by the action of the springs s s; the tumbler t (see fig. 8) having by this time disconnected itself from the bar t' so as to allow the dog to be moved independently of the shaft P. The forward movement of the jaws toward the comb takes place during the time that the comb and gauge-plates are at rest in front of the endless apron, and while the blank space of the segment-gear H is passing, without driving, the pinion h. Extending across and below the space traversed by the jaws O, is a moving platform composed of a number of parallel endless cords or belts w w, revolving around drums or cylinders T T', which are grooved so that the cords may be kept at a proper and uniform distance apart. Motion is communicated to the platform by means of a stud, w', on the face of the spur-gear C'', which, as the gear revolves, comes in contact with one of the radial arms on the end of the shaft of the drum T, and causes it to revolve intermittently. The movement is effected at the time when the jaws have receded fully from the comb, and have opened, and just before they commence their return towards the comb, (fig. 5.) On the shaft B, and revolving with it, is a grooved cam, U, which receives a stud on the horizontal lever U', and gives lateral vibration to it. The arrangement is shown partly in fig. 1, and more distinctly in the elevation, fig. 7, and plan of the same, fig. 8. The lever U' is connected by a rod with another lever, U'', vibrating in a vertical plane, on a joint in the lower part of the frame-

work A, and extending upwards between the slides V V, firmly secured to and extending across the frame A A, under the moving platform w w. A plate, x, having hooks or fingers x' x' extending up between and above the cords of the platform, is made by the lever U" to traverse along the slides V V from the driven end of the platform to the other end and return while the movement of the platform itself is going on. The hooks or fingers x' x' sweep the bristles which have just been deposited by the now open jaws upon the platform towards the deposit-box W, which receives by the movement of the platform those bristles which have been swept along by a previous movement of the fingers x' x'. The deposit-box is covered by an endless apron, W', which moves simultaneously with the platform w w, being connected therewith by cord and pulleys w' w", and aids the onward movement of the bristles after being gathered towards the box. The sides of the box W are thin enough to have a slight vibratory motion given them for the purpose of gently striking the bristles endwise so as to bring their ends as near as may be into the same vertical plane. This is effected in the following manner: On the outer extremity of the shaft o is a ratchet-cam, Y, giving motion in opposite directions at the same time to two rods y y, each of which slides in permanent bearings near its ends, and is kept in contact with the cam by springs or equivalent devices. These rods have each a stud, y', so fixed that one stud shall be made to strike one side of the box W and the other stud shall strike the other side, which, being repeated rapidly by the action of the cam Y, produces a tremulous motion endwise of the bristles in the box and causes them to become arranged uniformly.

The operation of this machine is as follows:

The tangled, irregular, matted mass of bristle is loosened or spread a little by the hand and laid upon the apron E. Motion being given to the main driving-shaft B, the operation is commenced by the revolution of the feed-roller e and endless-apron E, which carry the bristles by a regular movement to be operated on by the teeth of the picker or hatchet on the shaft F, when they will fall upon the lower apron E', which they will reach in a looser and more regular condition than when first fed to the machine. The apron and roller E' e' will now, by their intermittent movement, have presented some bristles for the action of the comb J. This makes two revolutions, by means of the shaft g, consecutively, while the main shaft B makes two-thirds of a revolution, passing each time, near the apron and roller E' and e' and combing those bristles which had been forced out from between them. During the other third of the revolution of the main shaft the comb J is at rest in the position shown in fig. 4, with its teeth separating the ends of the bristles just combed, and which project through between the comb teeth, while the gauge-plates M and k press upon the bristles below and above and keep them in a proper and parallel position to be seized by the jaws O O. This is done at the close of the last-named third part of the revolution of the shaft B, and is effected by the turning of the dogs u u, as hereinbefore described. About the time that this closing of the jaws takes place the apron and roller E' e' are moved so as to push the bristles as far as may be into the jaws O and bring forward other bristles to be operated on by the comb, while the jaws are being retracted, dragging the bristles they hold out from between the teeth of the comb and the gauge-plates M k until the jaws are far enough back to be opened by the cam R on the shaft P and drop their charge on the platform w w. While this is being performed the lower gauge-plate M has dropped down, its rock-shaft L being relieved from pressure by the stud n on the spur-gear D, and the comb is carried twice down through the bristles again presented by the apron and roller E' e', when it again comes to a rest, as shown in fig. 4, and awaits the return of the jaws. When the jaws are opened they allow the bristles to fall upon the cords of the platform w w so as to lie across it and parallel with each other and be immediately swept towards the deposit-box W by the fingers x' x', which return to their position before the jaws commence their movement again towards the comb. This quick action of the fingers x' x' is effected, as before described, by the cam U and horizontal and vertical levers U' U". The platform and endless apron over the box W have made their movement in the same time as the fingers x' x', and have carried into the box W those bristles which were swept towards it by a former action of the fingers x' x'. The jaws now again move towards the comb, and the operation is repeated for every revolution of the main shaft B; and as fast as the bristles are collected in the deposit-box W and shaken into uniformity of ends they can be taken away in bundles by hand or carried by machinery to be assorted into lengths and placed with their butts and flags each in one direction. It should be observed that the cams m m on the shaft g and crank-wrist I are brought in contact with the arms k' k' of the gauge-plate k as soon as the comb-teeth have swung out far enough from the apron and roller E' e' to be clear of the bristles held by them, so that the gauge-plate shall force out from between the teeth anything which it is not desirable to retain. This is done at every revolution of the comb, the gauge-plate k resuming its proper position by the action of the spring l as soon as the cams m m have passed the arms k' k'.

I intend that my machine shall be connected, by endless cords, belts, aprons, or any equivalent devices, with the machines for combing and for separating bristles, for which Letters Patent of the United States were granted to me under dates of February 20, 1866, and April 17, 1866, as shown on sheet No. 3 of the drawings hereunto attached, where

Figure 9 is the herewithin described machine;

Figure 10 is the comb; and

Figure 11 is the separator.

Having thus fully described my invention, what I claim as new therein, and desire to secure by Letters Patent, is—

1. The endless apron and feed-roller E e, with the picker F', on the shaft F, having a continuous motion, as described, in combination with the intermitting endless apron and feed-roller E' e', operated substantially as herein set forth for the purpose described.

2. The comb J, with its appurtenances, consisting of the comb-stock and teeth, stem J', gauge-plate k, arms k', and spring l, all combined substantially as and for the purpose set forth.

3. The manner of operating the comb J, by means of the shaft g and crank-wrist I, in combination with the sliding stem J' and its socket, and with the adjustable joint K, and cams m m, substantially as set forth; and this I claim, whether the intermittent motion of the comb be derived from the action of the segment H, in the pinion h, or from any equivalent device.

4. The comb J and its appurtenances, in combination with the gauge-plate M, operated by means of the rock-shaft L, stud n, and toe n', or their equivalents, substantially as and for the purpose hereinbefore set forth.

5. The jaws O, furnished with one or two yielding lips, and the levers O'' O'', in combination with the cam R and springs s, and either with or without the toggle-joint levers q q, all combined with and operating by means of the windlass P', and chains, or any equivalent device, substantially as and for the purpose set forth.

6. The dogs u u, on the shaft t'', in combination with and operated by the tumbler t, slotted bar t', and lever v, or its equivalent, substantially in the manner and for the purpose described.

7. The endless platform w w, arranged substantially as described, and having an intermittent motion, in combination with the endless apron W', over the deposit-box W, for the purpose set forth.

8. The sweeping fingers x' x', operating as set forth, and by means substantially as described, in combination with the moving platform w w.

9. I claim the cam Y, rods y y, and studs y' y', when combined substantially as herein described, for the purpose of giving a tremulous lateral movement to the sides of the box W, for the object set forth.

10. I claim the combination of the jaws o with the comb J and the endless apron and feed-roller E' e', each with their several appurtenances arranged and operating substantially as and for the purpose set forth.

NATHAN H. SPAFFORD.
